BALL POINT WRITING IMPLEMENT

Isidor Chesler, Oceanport, N. J., assignor to Eagle
Pencil Company, a corporation of Delaware

Application February 14, 1945, Serial No. 577,773

3 Claims. (Cl. 120—42.4)

1

The present invention relates to writing implements more particularly of the type that may properly be designated as ink pencils.

It is among the objects of the invention to provide an implement of the above type of simple, compact and relatively inexpensive construction made up entirely of rigid elements, readily machined or molded at small cost, and easily assembled and which is correspondingly rugged, which affords an almost indefinite supply of ink and does not require refilling for a period of years, which will unfailingly make an ink line that is substantially smudge-proof and requires no blotting and this without the slightest danger of flooding, regardless of the temperature, humidity or atmospheric pressure of the environment.

According to the invention, the supply of ink is confined in an elongated capillary passageway conformed in a core plugging the barrel and preferably by appropriate groove conformation on the face of the plug forming in cooperation with the barrel wall the desired capillary void which desirably may be in helical form. The ink being made to fill the capillary passageway in the absence of entrapped air is propelled toward the writing point under atmospheric pressure through a vent in the barrel. The point is movable, preferably of the ball type and is normally maintained against its outer seat by the weight of the column of ink in the passageway thereby to preclude leakage.

In the accompanying drawings in which is shown one of various possible embodiments of the several features of the invention,

Fig. 1 is a view in longitudinal cross-section through the implement.

Fig. 2 is a transverse sectional view on an enlarged scale showing the writing tip construction, and

Fig. 3 is a view in transverse cross-section taken on line 3—3 of Fig. 2 with the ball removed.

Referring now to the drawings, the barrel 10 of the implement is cylindrical throughout its main length but desirably tapers or is generally frusto-conical as at 11 at its forward end.

Plugged within the barrel is a core 12 which may be of metal, plastic or the like, machined or molded and which snugly fits the cylindrical bore and has a reduced conical end 13 snugly fitting the conical writing end 11 of the barrel. This core affords one or more capillary conformations for accommodating the ink in one or more columns. While the ink may thus be accommodated in bores through the core, it is preferable to accommodate it in one or more elongated

2

capillary conformations defined between the bore of the barrel and the surface of said plug. Desirably the conformation is a helical groove 14 in the wall of the core, of uniform depth, in the order of .10 inch and of width desirably somewhat less than its depth as shown. The root diameter of the groove is desirably constant as shown, the depth of the groove correspondingly decreasing as shown, at the conical end. The groove does not extend clear to the upper end of the core 12 but the core has a smooth uninterrupted cylindrical upper end 15, with an axial bore 16 therein of relatively large diameter, which communicates with the groove 14 through a radial bore or port 17 of very small diameter.

The lower or writing point end of the core also has an axial bore 18 therein, which communicates through a radial bore 19 with the lower part of the helical groove 14 which groove terminates 20 before the lower end of the core as at 14' so that the conical end of the core, below the end 14' of the groove, which coacts with the inner wall of the barrel serves as a stopper. The threaded nipple 24 of the tip is screwed into the correspondingly tapped socket 25 in the forward end of the core 12, with the shoulder 26 of the tip seated against the forward open end of the barrel, thereby causing the conical end of the core tightly to be seated in the conical front 11 of the barrel as shown.

30 The implement has a tip 20 which accommodates the movable writing point preferably in the form of a ball 21. The tip has a longitudinal bore 22 communicating through a reduced axial bore 23 directly with the surface of the ball 21 mounted in the forward end of said tip. The backstop 27 for the ball is thus an integral part for the tip. The ball is held against said backstop by the inturned rim 28 of the tip. Desirably the backstop is roughened as, for instance, by 35 milling as at 29 and so the flow of ink can take place to the annular chamber 30 about the inner end of the ball.

40 The ink groove 14 is vented to atmosphere at its upper end through the bore 16 and through 45 the preferably axially disposed vent hole 31 in the cap plug 32 threaded at 33 into the upper end of the barrel.

45 The ink maintained in the capillary passage 14 preferably extends from the ball 21 to a point 50 34 substantially below the upper end of groove 14. Therefore no ink will escape under expansion with rise in temperature. Since the helical passageway 14 of the substantial volumetric capacity shown might not afford adequate capillarity, were the ink of the liquid or free flow type,

a thick paste-like ink is used which will thus not flow out of the groove when the implement is held in inverted position.

In charging the implement, the thick ink may be readily forced through the writing end thereof (with its tip removed, of course), and if originally devoid of entrapped air, will force the air out ahead of it as it passes into and fills the capillary passageway.

The operation of the implement, though probably clear from the foregoing, will be briefly set forth. The weight of the column of pasty ink devoid of entrapped air in the capillary vessel, chamber or passageway, will press against the ball writing point 21, which under such pressure is normally urged against the inturned lip 23, the ball acting as a valve to preclude leakage. In writing, the ball 21 picks up such pasty ink chiefly from axial bore 23 and also from the cavity 30. The pasty ink, due to the weight thereof, is always reliably brought in contact with the ball at bore 23.

The ball writing point delivers only sufficient ink to make a thin smudge-proof line that requires no blotting.

As previously noted, rise of temperature will not cause flooding, because the pasty ink will simply expand into the upper end of the helical groove. Under subatmospheric pressure, say in airplane travel, the pen will feed somewhat less freely and unlike ordinary fountain pens, it will not flood.

The radial bore 17 being as shown of small diameter, (.025 or .030 inch) much smaller than that of a vent hole such as hole 31, acts as a dashpot or air-cushion which releases the air slowly to prevent the pasty ink from surging forward past the upper end of the core 12 should the implement be hurled forward under high acceleration or deceleration of a vehicle. There is thus no danger of ink escaping from the open vent 31. Yet bore 17 despite its small diameter maintains a permanent vent of the ink column and thus precludes blocking of flow by vacuum.

The helical cavity affords a supply of ink sufficient to last for some months. When the ink has been used up, if the implement is still serviceable, it will have to be sent back to the factory or to a service station for refilling.

As many changes could be made in the above construction, and many apparently widely different embodiments of this invention could be made without departing from the scope of the claims, it is intended that all matter contained in the above description, or shown in the accompanying drawings, shall be interpreted as illustrative and not in a limiting sense.

Having thus described my invention, what I claim as new and desire to secure by Letters Patent of the United States is:

1. A writing implement, comprising a barrel having a cylindrical bore with a conical tapered writing end, a core having a conical end seated in the corresponding end of the barrel, an axially bored tip threaded into the reduced end of said core and abutting the tip end of said barrel, thereby retaining the conical end of said core tightly sealed in the conical end of said barrel and plugging the latter, a ball writing point in the forward end of said tip, said tip having a lip serving as a seat for said ball, a helical groove about said core terminating before the forward end of said core and defining with the inner wall of said barrel a capillary passageway, said barrel having a vent communicating with the upper end of said

passageway, and a transverse bore in said core near the lower end of said passageway communicating with the axial bore of said tip.

2. A writing implement, comprising a barrel having a cylindrical bore with a conical tapered writing end, a core having a conical end seated in the corresponding end of the barrel, said core having a helical groove thereabout, said helical groove extending about the major portion of the length of the core and thence along the conical tip of the core, said groove terminating before the forward end of said core and having a substantially uniform root diameter, the upper end of said core being of continuous cylindrical form and snugly fitted into said barrel, said core having an axial bore in its upper end and an axial bore of smaller diameter in its conical end, an axially bored tip threaded into said latter bore and abutting the tip end of the barrel, thereby retaining the conical end of said core tightly sealed in the conical end of said barrel below the end of said groove and plugging said barrel, a ball writing point in the forward end of said tip, said tip having a lip serving as a seat for said ball, and a pair of radial bores in said core communicating from the respective axial bores to the helical groove therein, said barrel having a vent at the upper part thereof.

3. A writing implement comprising a barrel having a cylindrical bore with a conical tapered writing end, a core conformed to the bore of said barrel and having a conical forward end fitting snugly in said tapered writing end of the barrel, said core having a helical ink accommodating groove thereabout terminating at a substantial distance before the forward end of said core, said groove coacting with the inner wall of said barrel to form a capillary passageway, part of the length of said passageway being charged with pasty ink, a tip having an axial bore and secured in an axial bore through the forward end of said core and protruding from the barrel, said tip having a shoulder abutting the forward end of said barrel and thereby firmly sealing the conical end of said core in and against the conical forward end of the barrel to plug the latter, an axial bore into the rear end of the core, transverse bores in said core extending from the inner part of said helical groove to said bores in the forward part of the core and the rear end of the core respectively, a vent at the upper end of said barrel leading into the axial bore at the rear end of said core and a small port constituting the sole communication between the capillary passageway and the vent, said port being restricted and of area much smaller than said vent and serving as an air cushion or dashpot to prevent surging of the ink forward under high acceleration or deceleration of a vehicle.
